ELECTROPHONIC FILTER

Georges Mabboux, Paris, France

Application November 18, 1931, Serial No. 575,911
In Belgium November 26, 1930

12 Claims. (Cl. 179—1)

The present invention relates to electrophonic filters and, more particularly, to those of the type adapted to be used for modifying the sound emitted in assemblies employed for sound pictures, radio telephony and the like.

Electrical filters based upon the Wheatstone bridge are already in use wherein the various branches are provided with resistances or impedances, the latter being generally fixed.

One of the objects of the invention is to provide a slide-bridge type of Wheatstone filter in which two branches of the bridge are provided with a sliding contact which may be displaced along an impedance (ohmic resistance, self-inductive impedance or capacity) whose electrical properties may be distributed in accordance with any predetermined law, the other branches of the bridge being provided with adjustable impedances.

Another object is to provide a Wheatstone assembly of the type described in which impedances are connected to certain of the branches through the intermediary of transformers whose effect may be varied or whose coefficient of transformation may be adjusted at will.

An additional object is to provide a Wheatstone assembly in which at least two of the branches are systematically coupled so as to produce a variable effect or a change in transformation ratio.

A further object is to provide a Wheatstone assembly of the type hereinabove described wherein means are included for changing operation instantaneously from any given intermediate adjustment to certain extreme adjustments and inversely.

Another object still is to provide a stand or similar supporting structure with handles, switches and the like, permitting a musician or operator to quickly and easily modify the action of the filter so as to change the quality, volume, timbre, etc., of the sound being emitted continuously.

Still further objects will appear in the course of the detailed description now to be given with reference to the accompanying drawings, in which:

Figure 1 is a wiring diagram showing one illustrative embodiment of the invention;

Figure 2 is a wiring diagram of a second possible embodiment;

Figure 3 represents, diagrammatically, a third form of the invention;

Figure 4 illustrates, in perspective, a stand adapted to support structures of the type repre-

sented in Figures 1 to 3 and including a plurality of manual controls for instantaneously modifying the action of the latter.

Referring to Figure 1 of the drawings, there is shown a Wheatstone bridge assembly in which conductors a^1, a^2 receive current, while conductors b^1, b^2 deliver current, or conversely. Conductor a^1 is provided with a sliding contact A capable of being displaced along a resistance (potentiometric hook-up) so that part R^1 of said resistance lies in branch a^1, b^1 and part R^2 in branch a^1, b^2 . Branch b^1, a^2 is provided with an adjustable capacity C^1 while branch a^2, b^2 includes an adjustable self-inductance L^1 .

When contact A is moved into position so that the value of resistance R^1 is approximately zero, the filter has the characteristics of a so-called "low-pass" type; that is to say, it permits the passage of only low frequencies. If, on the other hand, contact A is displaced so as to render the value of resistance R^2 nearly zero, the filter presents the characters of a so-called "high-pass" type; that is to say, one, which permits the passage of only high frequencies.

By adjusting the variable impedances of the four branches of the slide bridge, it thus becomes possible to modify the characteristics of the filter at will and progressively, if desired, from the "low-pass" to the "high pass" type as well as to vary the frequencies of resonance and to eliminate the desired frequencies.

If it be desired to attenuate the effect of the variation in impedance on the input and output circuits of the bridge as a function of the frequency, the latter may be provided (Figure 2) with oscillation dampening impedances presenting, preferably, characteristics which are the inverse of those of the input and output circuits and which can, under certain conditions, be reduced to simple resistances such as R^3 or R^4 positioned across one of the diagonals of the bridge, resistance R^4 being provided with some such adjusting element as H.

The form of assembly represented in Figure 3 is similar to the one illustrated in Figure 2. However, it is to be noted that capacity C^1 of branch b^1, a^2 in the latter is replaced by a resistance R^5 or any other impedance (series, parallel, or complex) while self-inductive impedance L^1 of Figure 2 is replaced by a resistance R^6 or by any other form of impedance (series, parallel, or complex).

In order to vary the selectivity of the electrophonic circuits, recourse may be had to adjustable damping resistances connected, preferably, to at

least one of the impedances of branches b^1 , a^2 and b^2 , a^2 , i. e., in the example shown, to at least one of resistances R^5 or R^6 . These damping resistances such as R^7 may be composed, at least in part, by a fraction taken from the charge impedance, for example, from R^3 , utilizing a potentiometric hook-up provided with a sliding contact F .

The assembly may further be provided with impedances such as resistance R^8 , a self-inductance or a condenser acting on said filter, for example, on impedance R^5 through the intermediary of a transformer T^1 fitted with a control D and of a variable coupling type or having a variable coefficient of transformation.

A systematic coupling may further be introduced between any two branches of the bridge (for example, between branches b^1 , a^2 and b^2 , a^2) through the intermediary of a transformer T^2 fitted with a control E , the coupling being variable or having a variable coefficient of transformation.

The assembly represented in Figure 3 is further provided with means for instantaneously passing from any position of intermediate adjustment to any one of the extreme conditions of low pass or high-pass operation. To this end, shunt circuits are separately connected to resistances R^1 and R^2 and sliding contact A and a pair of switches are introduced into the two circuits in the manner shown in Figure 3. By reference to the drawings, it will at once be seen that, if control M connected to one of the switches is moved into contact with terminal x^1 , and control N of the other switch into contact with terminal x^4 , resistance R^2 will be cut out of the circuit. Contrarywise, when elements M and N are moved into contact with terminals x^2 and x^3 resistance R^1 will be cut out. If elements M and N are brought back into their intermediate positions as shown in Figure 3, the original state of operation between high and low-pass is reestablished.

In order to permit large scale manufacture of filters of the type described so that the latter may be coupled to electrophonic circuits in current use having impedances of their own, transformers T^3 and T^4 of variable transforming ratio are mounted in the input and output circuits of the filter, the controls for varying the operating ratios of said transformers being arranged for separate or simultaneous adjustment. With these auxiliary structures, the filter is capable of operating without being effected by the characteristics of the circuits to which it is coupled.

Figure 4 represents a filter and controls of the type shown in Figure 3 mounted for operation in assembled relation on an operating support. Here, element 1 is a stand of the type commonly employed for orchestra leaders and is provided with a box 2 designed to receive any one of the types of filter shown in Figures 1 to 3. A series of control handles A , F , M and N and dials D and E traverse the walls of element 2 and have each a function corresponding to that of the elements bearing the same reference characters in Figure 3. If desired, an oscillatable pedal H similar to the pedals of expression used on organs may be added and may control the intensity of sound transmitted by varying damping impedance R^4 . This pedal should be mounted so that it conserves any given position of adjustment when released.

With a stand of the type described, a musician or operator seated in a hall in which a sound film is being shown may correct imperfections in re-

production in the course of the audition and may equalize the sonorous quality of successive sections of the film which as ordinarily produced frequently present considerable variations. It will be seen that the filter forming the subject matter of the present invention may be used to render reproduction homogeneous both as to timbre and intensity.

It is also obvious that, by manipulating the various operating handles, any desired interpretation may be given to the music being reproduced in accordance with the taste, preference, or personal interpretation of the musician-operator. The musician may moreover, render the sound being produced very shrill or very low so to accentuate sound effects produced by a drum or other instrument of percussion and modify the sound accompanying the explosion of a cannon or the whistle of the locomotive.

If it be desired to use the filter for recording a musical work, it should be intercalated in the circuit connecting the microphone to the recording apparatus. The correction of a first recording operation may be effected by rerecording in a similar manner. The invention may be further applied to the control of the quality of radio emission, the musician following and correcting the latter with a receiving apparatus while manipulating a filter connected either to the emitting or receiving stations.

What I claim is:—

1. In combination with an electrophonic circuit, a filter including a Wheatstone bridge circuit, said bridge circuit comprising an input circuit and an output circuit, branches connecting each conductor of the input circuit with each conductor of the output circuit, an impedance in each branch, one pair of adjacent branches having their impedances serially connected to form a common impedance, and means for simultaneously distributing said common impedance between said pair of adjacent branches in varying proportions.

2. A structure as defined in claim 1 in combination with an impedance connected across a diagonal of said bridge circuit.

3. A structure as defined in claim 1 in combination with a variable impedance connected across a diagonal of said bridge circuit.

4. A structure as defined in claim 1 in combination with a variable resistance connected across a diagonal of said bridge circuit.

5. In combination with an electrophonic circuit, a filter including a Wheatstone bridge, said bridge having a variable capacity inserted in one branch thereof, a variable self inductance inserted in a second branch thereof, a pair of branches including an impedance, and means for distributing said impedance in varying proportions between said last named branches.

6. In combination with an electrophonic circuit, a filter including a Wheatstone bridge circuit, said bridge circuit comprising an input circuit and an output circuit, branches connecting each conductor of the input circuit with each conductor of the output circuit, a variable impedance in each branch, and means for simultaneously increasing one of said impedances while decreasing another.

7. In combination with an electrophonic circuit, a filter including a Wheatstone bridge circuit, said bridge circuit comprising an input circuit and an output circuit, branches connecting each conductor of the input circuit with each con-

ductor of the output circuit, a variable impedance in each branch, an impedance inserted diagonally across said bridge circuit, and means connected to one of said branches for exerting a damping effect.

5. 8. In combination with an electrophonic circuit, a filter including a Wheatstone bridge, said bridge having branches provided with variable impedances and also having an impedance inserted diagonally thereacross, said bridge further having potentiometric means extending from one branch thereof to the diagonal impedance.

9. In combination with an electrophonic circuit, a filter including a Wheatstone bridge, said bridge including an impedance distributable between a pair of adjoining branches, means for distributing said impedance in varying proportions between said branches, and switch means operative to cut out the impedance forming part of 10 either one of said branches.

10. In combination with an electrophonic circuit, a filter including a Wheatstone bridge circuit, said bridge circuit comprising an input circuit and an output circuit, branches connecting each conductor of the input circuit with each conductor of the output circuit, a slide wire se- 15

rially connecting one pair of adjacent branches, an impedance in each of the other branches of said bridge circuit, and means associated with said slide wire to distribute resistance between said pair of adjacent branches.

11. In combination with an electrophonic circuit, a filter including a Wheatstone bridge circuit, said bridge circuit comprising an input circuit and an output circuit, branches connecting each conductor of the input circuit with each conductor of the output circuit, an impedance in each branch, means for inductively and adjustably coupling the impedance in one branch with the impedance in another branch.

12. In combination with an electrophonic circuit, a filter including a Wheatstone bridge circuit, said bridge circuit comprising an input circuit and an output circuit, branches connecting each conductor of the input circuit with each conductor of the output circuit, a resistance inserted in one of the branches of said bridge, an impedance in another branch, means for inductively and adjustably coupling said impedance with said resistance, and impedances in said other branches.
